ROBERT M. FOLSOM, OF READING, MASSACHUSETTS, ASSIGNOR TO NEW ENGLAND FUEL
AND TRANSPORTATION COMPANY, TRUSTEES

APPARATUS FOR PRODUCING GAS AND COKE

Original application filed May 4, 1927, Serial No. 188,764. Divided and this application filed July 2, 1928.
Serial No. 289,726.

My invention relates to apparatus for producing gas and coke, and is particularly concerned with an improved retort coke oven that may be charged with a minimum of mechanical leveling. The method herein described forms the subject matter of my co-pending application Serial No. 188,764, filed May 4, 1927, of which application the present application is a division.

10 The invention will be best understood from the following description when read in the light of the accompanying drawings illustrating the apparatus, while the scope of the invention will be more particularly pointed 15 out in the appended claims.

In the drawings:-

Fig. 1 is a longitudinal section of an oven and coal hopper constructed according to the invention with associated apparatus shown 20 in elevation, this figure indicating the charge of coal flowing into the oven;

Fig. 2 is a section of the oven on the line 2—2 of Fig. 1;

Fig. 3 is a plan of the roof of an oven constructed according to Fig. 1;

Fig. 4 is a plan on an enlarged scale of the roof of an oven at the charging hole;

Figs. 5 and 6 respectively are sections on the lines 5—5 and 6—6 of Fig. 4;

30 Fig. 7 is an elevation on an enlarged scale of the larry car as viewed from the right in Fig. 1;

Fig. 8 is a section of the chute and valve of the larry car hopper on the line 2—2 of Fig. 1;

Fig. 9 is a schematic diagram of one form of piping for the apparatus; and

Fig. 10 is a section on the line 10—10 of Fig. 9.

40 I will first describe by reference to the drawings a preferred example of the apparatus, it being understood that I am not limited to this example.

45 The drawings show a battery of narrow, high-chambered, horizontal coke ovens 1 separated by combustion chambers 3. Beneath the coke ovens and combustion chambers are parallel cross regenerators 5 of known construction for heating the air supplied the combustion chambers by way of

the ducts 7, the fuel for combustion purposes being supplied by gas nozzles 9. Herein each oven adjacent the center of its length is provided with a charging opening 11 having a removable cover 12, while near opposite ends 55 respectively each oven is provided with a gas offtake 13 in communication with a standpipe 15, the top bends 16 of various standpipes leading to gas collecting mains 17 at corresponding sides of the battery. As shown 60 each standpipe has a manually controlled valve 19 for establishing and interrupting communication with the respective mains.

As illustrated the battery at opposite sides 65 respectively is provided with a steam main 21, branch pipes 23 leading from these mains to the upper portions of the adjacent standpipes to provide for projecting steam jets along the top bends 16 of the standpipes for creating in each standpipe an ejector action 70 accelerating flow of gas from the respective ovens. Each pipe 23 conveniently may be provided with a controlling valve 25 for creating the ejector action when desired.

Herein the mains 17 are connected by a 75 cross over pipe 27, and discharge into a main 29 which leads to gas coolers 31. For drawing the gases from the ovens through the coolers exhausters 33 are provided, the desired degree of pressure in the collecting 80 mains 17 being maintained by automatic pressure controlling mechanism 35, the valve of which is indicated at 37.

As illustrated each oven at opposite ends 85 is provided with removable doors 39 which are removed when the oven is pushed. One of the doors 39 is shown as provided with a chuck hole 41 for entrance of a "leveling bar" 43, the chuck hole having a movable closure 45 for blanking the chuck hole when the leveling bar is withdrawn. Conveniently the leveling bar is so proportioned and arranged that it just clears the top and sides of the oven chamber.

Along the top of the oven are illustrated 95 tracks 47 supporting the wheeled larry car 49, the hopper of which is indicated at 51. As illustrated the hopper has the flared sides 53 which with the vertical baffle 55 cause the coal in the hopper to gravitate through the 100

chute 57 uninterruptedly in a continuous stream when the quick opening valve 59 is moved from its closed dotted line position in Fig. 7 to its open full line position by the valve operating handle 60.

5 I have found that by suitably preparing the coal and proportioning the parts of the apparatus the coal may be charged into each oven and distributed uniformly and evenly throughout its length without substantial mechanical leveling. As the phenomena underlying this action are not exactly known to applicant I will now describe the proportions of one apparatus and the method of operation which exemplify and will secure 10 this result, it being understood however that I am not limited to the proportions and dimensions and particular steps described as wide deviations in these may be made without departing from the spirit of the invention.

15 In this particular example of apparatus referred to the oven chamber is about 40 feet long between the inner sides of the doors 39, about 13 feet high, the height being of the order of one-third of the length, and 17 inches wide at the coke side of the battery, tapering to 15 inches wide at the pusher side of the battery, the coal space of the oven occupying about 620 cubic feet and extending 20 to within about 12 inches of the top of the oven chamber, and the walls of the oven being at about 2,300 degrees Fahrenheit during charging. In this oven the charging hole is 25 a rectangle (see Figs. 4, 5 and 6), the dimensions of which are 14 by 20 inches, the narrow side of this rectangle corresponding to the inside width of the oven at its top, while the long side lies in the direction of the length 30 of the oven, it thus being observed that the charging opening is materially elongated in the direction of the length of the oven. The larry car has a capacity upward of about 14 gross tons and is provided with a rectangular 35 chute the inside dimensions of which are 17 by 23 inches, being of corresponding geometric shape to the cross section of the charging hole. The coal preparatory to charging is pulverized, the degree of fineness being 40 such that about 80% of the coal will pass through a screen having one-eighth inch square holes.

45 As an example of the method of operating the above described particular example of apparatus, the pressure controlling valve mechanism conveniently may be set to maintain a pressure of the order of several millimeters of water above atmospheric in the two gas collecting mains at opposite sides of the battery. When an oven is to be charged, both valves 19 associated with that oven are opened, and the steam ejectors set in operation by opening the valves 25. The charging hole cover 12 having been removed, the larry 50 containing about 13 $\frac{3}{4}$ gross tons of coal is

55 moved to place the latter over the oven with the chute of the hopper presented to the charging hole. The valve 59 is then opened, preferably quickly, to allow the coal precipitately to enter the charging hole in a continuous stream sufficient to fill the charging hole as the coal gravitates through it. I have found, under these conditions, that with coal of for example about 3 percent moisture content, the entire charge will flow 70 into the oven and distribute itself therein evenly, except for occasional small surface irregularities, throughout the length of the oven without mechanical leveling. After the charge of coal has gravitated out of the larry, 75 the latter may be moved from over the oven, and the small pile of coal remaining on the oven roof about the charging opening may be swept into said opening as the coal gravitates thereto; and, when the coal has gravitated to below the top of the charging opening, the cover may be placed in position and the opening sealed. A single stroke of the leveling bar to just past the charging hole will then suffice to insure removal of any 80 hump in the coal that may then exist beneath the charging opening, or other small irregularities in the top of the coal that has been self-distributed as above described.

85 Conveniently, under some conditions of 90 operation, the hopper on the larry car may be charged with an amount of coal greater than that which corresponds to the volumetric capacity of the coal space of the oven, and in charging the oven all the coal from the hopper, or sufficient coal, may be allowed to flow into the oven to fill the latter to above the upper level of the coal space, whereupon the leveling bar may be entered into the oven to the full length of the latter and 95 withdrawn, which will compact the charge and pull from the oven any excess of coal 100 above that necessary to fill the coal space, such coal pulled from the oven being received in the usual known manner by the 105 spillage receptacle carried by the leveling machine.

110 My explanation of the above described phenomena is that the rapid generation of gas from the pulverized coal flowing into the oven, and possibly some entrapping of air by the rapidly entering coal, together with the withdrawal of gas from opposite ends of the oven, destroys that property of the coal which gives it its normal angle of 115 repose, and in effect gives the coal that property of a liquid which causes it to flow into a container through an orifice and distribute itself throughout the container by gravity.

120 I have found that normally best results 125 will be secured by abruptly initiating the flow of coal into the oven to the full coal conducting capacity of the charging opening, and by so proportioning the dimensions 130 of the charging opening, relative to both the

degree of fluidity of the cold coal leaving the larry, and the degree of fluidity of the coal that is distributing itself in the oven, that the coal is charged at such rate as will prevent it from becoming unduly sticky in the oven due to the liberation of tar or otherwise affected to cause its flow to be retarded after it enters the oven.

Ordinarily best results will be obtained with a high chambered oven, such as that described herein, and when the charging opening is materially elongated in the direction of the length of the oven. Preferably, for a given oven and coal, the charging opening is designed to handle the coal at about its normal moisture content, it being understood that the fluidity of cold coal decreases with an increase in its moisture content. When, under normal conditions, the moisture content of the coal is very high, and the apparatus is designed for coal of normal moisture content, it may be necessary to operate the leveling bar after from about 65 to 75% of the charge has entered the oven.

The best location of the charging hole will depend to some extent upon the degree of taper of the oven, it being observed that if the charging hole is at the exact center of the oven, and the latter is tapered, a greater volume of coal must be charged toward the coke side of the oven than toward the pusher side of the oven, and that at the same time the narrowing of the oven from the charging hole toward the pusher side due to its taper acts to retard the flow of coal in that direction, while the increase in width of the oven from the charging hole toward the coke side of the oven acts to facilitate flow toward the coke side of the oven. I have found that with an oven proportioned as above described the retarding effect on the flow of coal of the taper of the oven from the charging hole toward the pusher side of the oven will be about compensated for by the lesser volume of coal charged into that side, which results in permitting the charging hole to be placed at about the center of the length of the oven.

In practicing the above method, preferably gas is withdrawn at such rate, during charging, as to prevent a material rise of pressure in the oven. To this end the oven chamber at its top is preferably maintained at about atmospheric pressure during charging, so as to prevent escape and loss of gas or intake of air through the chuck hole and other oven openings and through the coal in the charging opening. This will prevent the emission into the open air of smoke during the charging operation, and save the rich gaseous products then rapidly generated. After charging, the ejectors may be shut off, whereupon the pressures in the tops of the ovens will become and be maintained slightly above atmospheric, which will maintain

the flow of gas into the collecting mains and also eliminate any draft effect which might otherwise exist tending to draw air from the regenerators through the oven floors.

In the appended claims by "horizontal retort coke oven" and words of similar import is meant that type of coke oven with which the coke is pushed horizontally from one of the oven ends, the oven chamber having exteriorly heated side walls which are spaced a relatively short distance apart as compared with the length of the chamber. By "elongated coke oven" and words of similar import is meant a coke oven having a coking chamber the length of which is so much greater than its height that coal having a normal angle of repose charged into the chamber through an opening in the oven roof will not fill said chamber up to the normal charge level as would occur, for example, with a "vertical" type oven or a horizontal oven having a chamber with relatively short, horizontal dimensions compared to its vertical dimension.

It will be understood that I am not limited to the examples of apparatus nor to the dimensions or proportions thereof herein described, but that within the scope of the invention wide deviations may be made from these without departing from the spirit of the invention.

I claim:

1. A narrow, horizontally elongated, high-chambered, retort coke oven of the horizontally pushed type for producing coke and gas from pulverized coal, having an oven chamber which is tapered in horizontal planes from one end of the oven to the other, said oven having a charging opening in its roof at about the middle point of its length, said opening being substantially as wide as the top of the oven chamber but being materially elongated in the direction of the length of the oven, the effective cross-sectional area of said opening in horizontal planes being relatively small as compared to the cross-sectional area of the oven chamber in horizontal planes, gas offtakes communicating with the upper part of said oven above the coal space therein at opposite sides respectively of said charging opening, and means for delivering coal to said opening to the full coal conducting capacity of the latter.

2. A narrow, horizontally elongated, high-chambered, retort coke oven of the horizontally pushed type for producing coke and gas from pulverized coal, the height of which oven is of the order of a third of its length, having an oven chamber which is tapered in horizontal planes from one end of the oven to the other, said oven having a charging opening in its roof at about the middle point of its length, said opening being substantially as wide as the top of the oven chamber

but being materially elongated in the direction of the length of the oven, the effective cross-sectional area of said opening in horizontal planes being relatively small as compared to the cross-sectional area of the oven chamber in horizontal planes, gas offtakes communicating with the upper part of said oven above the coal space therein at opposite sides respectively of said charging opening, and means for delivering coal to said opening to the full coal conducting capacity of the latter.

In testimony whereof, I have signed my name to this specification.
